UNITED STATES PATENT OFFICE.

JOSEPH W. BISHOP, OF MUSKEGON, MICHIGAN, ASSIGNOR TO THE BRUNSWICK-BALKE-COLLENDER COMPANY, OF WILMINGTON, DELAWARE, A CORPORATION OF DELAWARE.

COMBINED PHONOGRAPH AND RADIO APPARATUS.

Application filed June 30, 1924. Serial No. 723,114.

This invention relates to a combined phonograph and radio apparatus which may be enclosed in a cabinet of the type shown in the application of Martin Nystrom, Serial 5 No. 713,128, filed May 14, 1924, or in any other suitable cabinet.

The object of my invention is to provide a combined phonograph and radio receiving set, both of which make use of the same amplifying horn, selectively.

More specifically the object of my invention is to provide a portion of the neck of an amplifying horn which is adapted to be brought into operative relationship with either the 15 tone-arm of a phonograph or the loud speaker of a radio set, all from the outside of the cabinet.

In the accompanying drawings forming a selected embodiment of my invention,

20 Fig. 1 is a front elevation of a portion of the cabinet containing my invention.

Fig. 2 is a vertical section through Fig. 1.

Fig. 3 is a section on the line 3—3 of Fig. 2, and

25 Fig. 4 is a section on the line 4—4 of Fig. 2.

Referring now to the drawings, 1 designates a cabinet in which is enclosed a phonograph having the tone-arm 2, turn-table 3, reproducer 4 and amplifying horn 5. Also 30 contained in the cabinet is a radio receiving set indicated at 6 and having a loud speaker 7 to which is connected a tubular neck 8.

A motor-board 9 is provided with an opening 9' which registers with the tone-arm 2 and with the upper end of a neck 10 which is connected at its lower end with a block 10' in which the small end of the amplifying horn 5 is entered. A portion 11 of the neck 10 is made integral with the loud speaker neck 8 and this one piece element designated 11' generally in Figs. 2 and 4 is provided with guides 12 which slide in guideways 13 on the neck. An operating rod 14 is connected to this one piece element 11' and it extends 45 through the wall 15 of the cabinet and is provided at its outer end with a handle 16 whereby the one piece element may be moved laterally in the guideways to connect the amplifying horn operatively to the phonograph or to 50 the radio receiving set, as desired.

Referring to Fig. 4, it will be seen that the element 11' has a passageway 17 registering with the tone-arm and forming a continuous passage from the tone-arm to the amplifying

horn. It also has a passage 18 in the neck 8 which is adapted to be brought into registry with the part 10" of the neck 10 and which will then provide a continuous passage from the loud speaker 7 to the amplifying horn.

I provide means for limiting the movement of the one-piece element 11' so that at the extremities of its movement it will be in such positions that the passageways 17 and 18 respectively will come into exact registry with the amplifying horn. This means is exemplified by a pin 19 set in one of the guideways 13 and engaging a slot 20 in one of the guides 12. The above described means will permit adjustment of the element 11' to positions where it is in operative connection with either the phonograph or the radio receiving set, and it also permits intermediate adjustments whereby the tone of the reproduction may be varied, either when the phonograph or the radio receiving set is in use, by cutting down the volume of sound transmitted to the amplifying horn.

From the foregoing description it will be seen that I have provided a combined phonograph and radio receiving set using a common amplifying horn, together with means for readily connecting said horn operatively to either the phonograph or the radio receiving set.

I am aware that changes in the form, construction and arrangement of parts may be made without departing from the spirit and without sacrificing the advantages of the invention and I reserve the right to make all such changes as fairly fall within the scope of the following claims:

I claim:

1. In a device of the character described, a phonograph, a radio loud speaker, an amplifying horn, a neck between said amplifying horn and said loud speaker and phonograph, guideways formed integral with said neck, an element having guides fixed thereon and adapted to slide in said guideways, said element comprising two passageways, each passageway adapted to register with the horn and one adapted to form an operative connection between said horn and said phonograph, and the other between said horn and said loud speaker.

2. In a device of the character described, a phonograph, a radio loud speaker, an amplifying horn, a neck between said amplifying

ing horn and said loud speaker and phonograph, guideways formed integral with said neck, an element having slotted guides fixed thereto and adapted to slide in said guideways said element comprising two passageways, each passageway adapted to register with the horn and one adapted to form an operative connection between said horn and said phonograph, and the other between said horn and said radio loud speaker, and means arranged on said guideways and cooperating with said slotted guides for limiting the movement of said element.

3. In a device of the character described, a phonograph, a radio loud speaker, an amplifying horn, a neck between said amplifying horn and said loud speaker and phonograph, guideways formed in said neck, an element adapted to slide in said guideways and comprising two passageways, each passageway adapted to register with the horn and one adapted to form an operative con-

nection between said horn and said phonograph, and the other between said horn and said radio loud speaker, and means for limiting the movement of said element, said means comprising a pin set in one of said guideways and adapted to engage a slot in said element.

4. In a device of the character described, a phonograph, a radio loud speaker, an amplifying horn, means for operatively connecting said horn to either said phonograph or said loud speaker, selectively, said means comprising a sliding element having two passageways, each adapted to register with said horn and one adapted to form an operative connection between the horn and the phonograph, and the other between the horn and the loud speaker, and means for limiting the movement of said element, said means comprising guideways, a pin set in one of said guideways and adapted to engage a slot in said element.

JOSEPH W. BISHOP.
